COMBINATION HOLLOW FISH POLE AND REEL HOUSING

Lloyd J. LeRoue, Rte. 2, P.O. Box 2360,
Wapato, Wash. 98951

Filed Mar. 13, 1970, Ser. No. 21,903

Term of patent 14 years

Int. Cl. D22—05

U.S. Cl. D22—23

FIG. 1

FIG. 2

FIG. 1 is a left side elevational view of the combination hollow fish pole and reel housing embodying my new design in an extended position;

FIG. 2 is a right side elevational view in a collapsed position.

FIG. 3 is a right front perspective view in a collapsed position.

FIG. 4 is a left rear perspective view in a collapsed position as viewed from the bottom.

The broken lines are for illustrative purposes only and form no part of the claimed design.

I claim:

The ornamental design for a combination hollow fish pole and reel housing, substantially as shown and described.
